EYEGLASS CONSTRUCTION

George E. Nerney, Attleboro, Mass., assignor to
 Bay State Optical Company, Attleboro, Mass.,
 a corporation of Maine

Application March 30, 1934, Serial No. 718,113

1 Claim. (Cl. 88—47)

This invention relates to an eyeglass construction and more particularly to the lens-connecting portion of a pair of spectacles.

One of the objects of this invention is to provide an eyeglass construction which may be readily manufactured with a minimum amount of labor and from inexpensive materials. Another object is to provide a construction of the above character which will be simple, practical and thoroughly durable. Another object is to provide a construction of the above character which may be assembled for use with extreme ease and with few tools. Another object is to provide a construction of the above character which is neat and attractive in appearance and at the same time rugged. Another object is to provide a construction of the above character in which certain of the parts thereof are made inconspicuous to enhance the general appearance thereof. Another object is to provide a construction of the above character in which there is a snug fit between the lens and the parts connected thereto. Other objects will be in part obvious and in part pointed out hereinafter.

25 The invention accordingly consists in the features of construction, combinations of elements, and arrangements of parts as will be exemplified in the structure to be hereinafter described and the scope of the application of which will be indicated in the following claim.

In the accompanying drawing, in which is shown one of the various possible embodiments of this invention,

Figure 1 is an enlarged front elevation of certain parts of an eyeglass frame having my invention embodied therein;

Figure 2 is a horizontal sectional view taken along the line 2—2 of Figure 1, and

Figure 3 is a plan view of one of the blanks forming a part of the construction shown in Figure 1, before it is bent into the shape shown in Figure 1.

Similar reference characters refer to similar parts throughout the several views of the drawing.

To comprehend more readily some of the more important features of this invention, it might here be pointed out that certain difficulties are encountered in the assembly of frames such as the rimless type. Frames of this general nature are characterized by a series of lens-connecting means adjacent the opposite ends of the bridge and adjacent each endpiece having straps extending over the opposite plane surfaces of the lenses. The retailer receives these parts from

the manufacturer and must fit them to the lenses prescribed for the customer. Very often the lenses used in these frames are toric in shape and thus the straps adjacent the concave surfaces thereof must be bent with pliers or the like in order to conform with the shape of the lenses. Due to the minute character of these parts, this is a tedious task and may often result in a poor lens connection even when accomplished by experts. If an attempt is made to draw the arm 10 down upon the concave side of the lens often the threads on the screw or on the arm are stripped thus causing more bother and inconvenience. One of the objects of this invention is to provide a construction in which the several difficulties hereinabove mentioned as well as many others are successfully overcome.

Referring now to the drawing in detail, there is shown in Figure 1 a fragmentary portion of a lens 10 having any suitable peripheral shape. The plane surfaces of lens 10 are toric in shape, the front side 10a thereof being convex and the rear side 10b preferably concave (Figure 2).

Connected to lens 10 preferably by a screw 11 is a lens-connecting part generally indicated at 12 to be described more fully hereinafter. Part 12 may be connected to either side of the lens and may have connected thereto either the end of a bridge or an endpiece. Illustratively I have here shown a bridge member generally indicated at 13 secured to part 12 and having a depending end portion 14 to which a nose guard 15 is secured in any suitable manner.

Still referring to Figure 1, an element 16 is in engagement with a portion of the periphery 35 of lens 10 and secured to one side thereof substantially at its central portion is a strap 17 extending over the convex surface 10a of lens 10. Thus strap 17 appears on the front side of the resultant frame as surface 10a preferably forms 40 the front surface of the lens when the frame is worn. Strap 17 has an enlarged end portion 17a which may take any convenient shape although here shown as substantially square. End portion 17a, as best shown in Figures 1 and 2, is sufficiently large to carry a countersunk hole 18 into which the head 11a of screw 11 fits. Furthermore, hole 18 is in registry with a hole 19 (Figure 2) extending through lens 10.

As more clearly shown in Figures 1 and 3, a strap 20 is secured to element 16 substantially near the central portion thereof and extends over the concave surface 10b of lens 10. Strap 20 has an enlarged end portion 20a having formed therein a threaded hole 21 into which screw 11 55

is threaded (Figure 2). As best shown in Figure 1, end portion 20a is much smaller than end portion 17a and in fact is usually made just large enough to support the threads of hole 21. Furthermore, that portion 20b of strap 20 located between end portion 20a and element 16 is also preferably smaller in width and thickness than the corresponding portion 17b of strap 17. Accordingly all portions of strap 20, and, as strap 17 is in registry therewith and on the front side of lens 10, it covers strap 20 completely when the frame is viewed from the front as worn. This helps in a large measure to make the lens-connecting part 12 as inconspicuous as possible, thus to enhance the general appearance of the frame.

When the lens-connecting part 12 is to be connected to the lens 10, the straps 17 and 20 are bent from the position shown in Figure 3 into a substantially right angular relation with respect to element 16. Of course this may be accomplished by the manufacturer before shipping to the retailer as is generally the case. The lens 10 is then fitted snugly against element 16 (Figure 2) and the screw 11 inserted in holes 18 and 19 to be threaded into hole 21 (Figure 3).

Rotation of screw 11 next draws the strap 20 down flush against the concave surface 10b of the lens into the position shown in Figure 2. Due to the small size of portion 20b of strap 20, the strap may be drawn down into a position flush with surface 10b without stripping the threads on the screw or in hole 21. This eliminates the necessity of bending strap 20 with pliers or the like in order to make it fit snugly against the surface 10b. Furthermore the small area occupied by end portion 20a of strap 20 allows this portion of the strap to be drawn snugly against the concave surface of the lens. Accordingly not only may the strap 20 be drawn into a snug fitting position, as shown in Figure 2, by the simple operation of rotating the screw, but, also, the resultant connection of the part 12 and the lens 10 is tight and well able to withstand wear and tear. Furthermore, while providing an extremely durable lens-connecting part 12, I have not sacrificed the ultimate general appearance of the

frame but to the contrary have enhanced the frame by making the strap 20 smaller and thus less conspicuous.

Accordingly it will be seen that I have provided a thoroughly practical and efficient construction in which the several objects hereinabove referred to are successfully accomplished.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

In eyeglass construction, in combination, a toric lens the edge of which extends acutely from the concave surface thereof and obtusely from the convex surface thereof, a part engaging a portion of said edge, a substantially rigid strap connected to said part and extending therefrom and engaging said convex surface, a pliable strap smaller in transverse cross sectional area than said rigid strap and connected to said part and extending therefrom over said concave surface, said pliable strap being adapted to be drawn into flat engagement along its entire length with said concave surface, the vertical angle between the upper edges of said straps and said part being acute, and said straps each having an enlarged portion formed on the free ends thereof, each of said enlarged portions having holes extending therethrough, and a screw extending through said holes and said lens and threadable into the hole in said pliable strap to draw said pliable strap against said concave surface, the axis of said screw being inclined with respect to the plane of said part, there being substantially less material at the junction of said pliable strap and said part than at the junction of said rigid strap and said part whereby when said pliable strap is drawn into substantially flat engagement with said concave surface there is no tendency, due to the relative rigidity of said rigid strap, to pull said pliable strap against the portion of said lens immediately adjacent the edge of the concave surface thereof.

GEORGE E. NERNEY.
